GOLF CLUB DIRECTION INDICATOR
ATTACHMENT

Allyn C. Fay, East Hempstead, N. Y.

Application March 31, 1951, Serial No. 218,611

6. Claims. (CL 273—163)

1

This invention relates to an attachment for golf clubs, and more particularly an attachment for a putter, or similar club, to enable a player, while practicing, to align the club with relation to the ball, in such a manner that he will obtain a definite visual indication of the direction in which club head is facing, to enable him to predetermine, with some degree of accuracy, the direction the ball will take when struck.

In putting, or other golf strokes in which angular direction is of vital importance, it is extremely difficult to align the club head in such a manner that the ball, when struck, will accurately follow a predetermined direction.

This requires accurate alignment of the face of a club, which is irregular in form, so that the ball when struck, will accurately follow the required direction toward the cup.

In order to acquire a high degree of skill in handling a club of this type, it is essential that a player practice a great deal in obtaining club head alignment and directional control.

The object of my invention is to provide an attachment for the head of a golf club, which will enable a player to simultaneously and accurately align the head of the club with the ball, accurately level the head of the club, with relation to the ground level, and accurately sight the direction in which the club head is facing, to enable the player to align the club with the cup, or other object, toward which the ball is to be directed.

A further object is to provide an attachment for a golf club head, which may readily and easily be attached to the head of a club, and is adjustable, so that it can be mounted on a wide range of club head shapes and sizes.

Another object is to provide graduations on the face of the attachment to enable a player to accurately align the ball with the striking surface of the club, and accurately center the ball with relation to the direction pointer.

A further object is to provide an indicating attachment, fitted with a spirit level, which can be readily adjusted to enable the player to adjust the level to conform to level of the ground, regardless of the angular position of the upper edge of the head of the club.

A primary object is to produce a unit which is rugged, can be produced at relatively low cost, and can be adjusted, mounted and utilized by persons having little or no specialized mechanical skill or training.

The accompanying drawings, illustrative of one:

2

embodiment of my invention, together with the description of its construction and the method of installation, operation, and utilization thereof, will serve to clarify further objects and advantages of my invention.

In the drawings:

Fig. 1 is a front elevation of the head of a putter, with an indicator attachment mounted thereon.

Fig. 2 is a plan view of the indicator attachment, attached to the putter head shown in Fig. 1, with a ball in place.

Fig. 3 is a vertical section through the putter head and the mounting flanges of the indicator, taken at 3—3, Fig. 2.

It will be understood that the following description of the construction, method of attachment, and operation of the golf club direction indicator, is intended as explanatory of the invention and not restrictive thereof.

In the drawings, the same reference numerals designate the same parts throughout the various views.

The direction indicator, shown in Figs. 1, 2 and 3, may be attached to the head 10, of a putter or similar golf club.

The attachment, which may be made of sheet steel, aluminum, a plastic material, or other sheet material, comprises a relatively flat top 11, of substantially rectangular cross section, with a triangular pointer 12, formed at the front end thereof.

An aperture 14, of square, rectangular, or other suitable contour, with large fillets 15, formed at the corners thereof, may be cut through the top, in substantial alignment with the normal striking position of the ball 16, to enable a player to see the ball, while the club head is swung through a short arc, preparatory to striking the ball in the usual manner.

The front end of the side members 17 of the indicator top may be folded over, as indicated in Fig. 3, the extreme end of the folded section being bent over to form a pair of flanges 18 and 19, substantially perpendicular to the top.

The rear portion of each of the side members 17 of the top may also be bent downward, as indicated in Fig. 3, to form a gripping flange 20, substantially perpendicular to the top, the outer end of each of the gripping flanges being folded back upon itself to form an auxiliary flange and retainer 21, for a clamp screw 22, which may be threadably supported by each of the doubled flanges.

A knurled, wing, or other suitable type of head

may be formed integral with one end of the clamp screw 22, a substantially spherical end 23 being formed at the opposite end of the screw, the spherical end supporting a swivel clamping head 24, in the manner indicated in Fig. 3, to enable the swivel head to assume an angular position, in conformity with the plane of the rear face 25, of the head of the club.

A formed plate spring 26, made of spring steel, or other suitable material, may be attached to the inner face of the left-hand flange 18, the opposite end of the spring engaging the face of the club head. A similar spring 27, may be attached to the opposite flange 19, in a similar manner. The left-hand spring comprises a flat base 28, which may be attached to the flange 18 by a plurality of rivets 29, spot welded to the flange, or otherwise attached thereto, and a clamping face 30, angularly disposed to the base, and spaced therefrom by an intermediate section, formed integral with the base, the clamping face 30 of the spring assuming an angular position in substantial alignment with the slope of the forward face 31 of the club head, in the clamping position, shown in Fig. 3.

In the free position, the clamping face of the spring assumes an angle considerably greater than that of the forward face of the club head, to enable the head of the club to distort the spring and place it under tension, in the gripping position.

The spring 27, attached to the right hand flange 19 of the indicator, may be constructed in a similar manner, the base 28, being located at the top of the spring, and attached to the flange 19, in the manner hereinbefore described.

The clamping face 32, formed integral with the base, assumes an angle in alignment with the plane of the forward, or striking face 31 of the club head, in the gripping position, although in its free position the spring clamping face is projected outward, to place the spring under tension in the gripping position.

In order to enable the player to accurately gage the position of the club head relative to the ball, a plurality of graduations 33, may be engraved or otherwise formed in the rear section 34, of the top, adjacent the aperture 14. The central graduation 35, may be in substantial alignment with the striking center of the club head when the attachment is mounted in the position, shown in Fig. 2. A plurality of equally spaced narrow graduations 33a, may be formed, as indicated at the left-hand side of Fig. 2, or wider spaced graduations 33b, shown at the right-hand side, Fig. 2, may be utilized, the spacing of the graduations being determined by the accuracy required in locating the striking face of the club head with relation to the center of the ball.

The plane of the top 11, of the indicator, would normally be located substantially parallel to the bottom edge 36 of the club head, which is usually located at ground level.

In order to level the club head, independently of the angular position of the plane of the indicator, a spirit level 31, may be mounted at the front end of the top 11, behind the pointer 12. The spirit level comprises a sealed, substantially cylindrical liquid-filled tube having hemispherically formed ends, the ends being supported by similarly formed heads 38, mounted at the ends of the tube, a packing 39 being inserted between each tube end and the head, to protect the spirit level tube from abrasion. An intermediate tubular casing 40 may be attached to, or formed inte-

gral with one head and permanently, or removably attached to the opposite head, by suitable attaching means. An oval parallel-edged slot 41, may be cut through the casing, to enable the player to observe the bubble in the spirit level.

A pair of ears 42, may be attached to, or formed integral with each of the tube casing heads, as indicated in Fig. 3. A pair of substantially vertical supports 43 may be cut out of the forward section of the top, the supports being bent upward, substantially perpendicularly to the plane of the top, to support the spirit level tube heads in the manner shown in Figs. 1 and 2. In the free position the ears 42, may be substantially parallel to the axis of the spirit level, as indicated at the left-hand side, Fig. 2. In the gripping position, the ears would be bent around the vertical supports, to grip the supports, thereby supporting the spirit level heads, in the manner indicated on the right-hand side, Fig. 2. The use of the ears 42, as a means of supporting the spirit level, enables the spirit level to be mounted in a level position, regardless of the plane of the flat top 11 of the indicator, or the upper edge 25 of the club head, to enable the player to accurately level the club head, parallel to the bottom edge 36, of the club head, regardless of the angular position of the other surfaces.

While a putter head of one type and cross-section is shown in Figs. 1, 2 and 3, the attachment may be used on a wide range of putter head constructions, the support flanges, formed integral with the top of the indicator, the springs, and the clamp screws being adjustable to accommodate a wide range of club head heights, thicknesses, and face angle positions.

In place of the pivoted head attached to the clamping end of the adjusting screw, other types of clamping surface may be provided, either formed integral with the screw, or attached thereto, depending upon the plane of the rear face of the club head, the thickness of the club head, and the range of club head thicknesses to be accommodated by a particular unit.

The size of the spirit level, the method of supporting the spirit level within the holder, and the method of attaching the spirit level holder heads to the indicator, may be altered considerably depending upon the size and type of spirit level used, the construction of the holder, and the construction of the indicator proper.

The indicator may be constructed of one piece of sheet material, formed and folded in the manner indicated in Figs. 1, 2 and 3, or the flanges may be formed separately, and welded, brazed, riveted, or otherwise attached to a separate top.

In place of the sheet metal construction, shown in Figs. 1, 2 and 3, the indicator may be formed of a laminated phenolic sheet material, or other plastic sheet, built up in sections of a laminated phenolic material, or molded in one piece of a suitable plastic material, the essentials of the construction and the method of supporting the indicator attachment on the club head being substantially as indicated in the drawings and hereinbefore described.

The form and contour of the aperture, formed in the top of the attachment, may be altered considerably, depending upon the size of the top of the indicator, and the area required to observe the golf ball, before it is struck by the club head.

The form and contour of the pointer formed at the front end of the indicator, shown in Fig. 1, 75 may be altered considerably, the angles of the

sides being varied to obtain an accurate guide for the club head.

The spacing of the graduations, formed at the rear end of the top of the indicator, and the overall width of the graduations, may be varied, depending upon the overall width of the indicator, the size of the aperture formed in the top, and the length of the ball striking area of the club face, which is to be utilized.

In training a player to properly align his club relative to the position of the ball and the cup, or other simulating object, used to determine the direction which the ball is to take, the club, with the attachment mounted thereon, and the spirit level properly adjusted relative to the bottom edge of the club head, may be utilized in the following manner:

The bottom edge of the club head may be levelled relative to the normal ground line by centering the bubble in the spirit level.

The player may observe the ball through the aperture formed in the top of the indicator, and align the ball with the club head face by means of the graduations formed in the top of the indicator.

By aligning the pointer along the projected line of travel between the ball and the cup, or other object, the club head is placed in the proper angular position to direct the ball along its correct path after it is struck by the player.

The arc of movement of the club head is the usual arc required for directing the ball to the cup, and would depend upon the distance between the ball and the cup.

It will be apparent to those skilled in the art that my present invention is not limited to the specific details described above and shown in the drawings, and that various further modifications are possible in carrying out the features of the invention without departing from the spirit and scope of the appended claims.

What I claim is:

1. A direction indicator for removable attachment to the head of a golf club, of the conventional type, for aligning said club head in the direction of movement of a ball, the club head remaining unaltered, comprising a top plate mounted above the club head, said top plate having an aperture formed therein, in substantial alignment with the ball-striking section of one face of the club, to enable a player to observe the ball through said aperture, a pointer formed integral with one end of said top plate in axial alignment with said aperture, said top plate having a pair of substantially parallel support members formed integral therewith, a spirit level mounted between said support members, a housing supporting said spirit level, and means adjustably attaching said housing to the support members, said spirit level indicating the normal ground level, relative to the club head, in its normal striking position, a pair of flanges formed integral with the sides of said top plate, adjacent one face of the club head, a pair of rear flanges formed integral with the end of said top plate, near the opposite club face, and means threadably attached to each of said rear flanges removably clamping the club head between said flanges.

2. A direction indicator for removable attachment to the head of a golf club, of the conventional type, for aligning said club head in the direction of movement of a ball, the club head remaining unaltered, comprising a top plate mounted above the club head, said top plate

having an aperture formed therein, in substantial alignment with the ball-striking section of one face of the club head, to enable a player to observe the ball through said aperture, a pointer formed integral with one end of said top plate in axial alignment with said aperture, the section of the top plate, adjacent the aperture, having a plurality of graduations formed therein, to indicate the position of the striking center of the club face, relative to the ball, said top plate having a pair of substantially parallel support members integral therewith, a spirit level tube mounted between the support members, a housing supporting said spirit level tube, each end of said housing having a pair of ears integral therewith, each pair of ears being adjustably attached to the corresponding support member, a pair of flanges formed integral with the sides of said top plate, adjacent one face of the club head, a plate spring attached to each of said flanges, each of said springs having a clamping face engaging the fact of the club head, a pair of rear flanges formed integral with the end of said top plate, near the opposite club face, a screw threadably attached to each of said rear flanges, the free end of each of said screws having a swivel head attached thereto, said flanges straddling the club head, the club head being clamped between the swivel head and the spring attached to the opposite flange.

3. A direction indicator for removable attachment to the head of a golf club, of the conventional type, for aligning said club head in the direction of movement of a ball, the club head remaining unaltered, comprising a top plate mounted above the club head, said top plate having an aperture formed therein, in substantial alignment with the ball-striking section of one face of the club, to enable a player to observe the ball through said aperture, a pointer formed integral with one end of said top plate in axial alignment with said aperture, a portion of the top plate adjacent the aperture having a plurality of graduations inscribed thereon, the center of said graduations being in substantial alignment with the center of the pointer, said top plate having a pair of substantially parallel support members formed integral therewith, a spirit level mounted between said support members, a housing supporting said spirit level, and means adjustably attaching said housing to the support members, said spirit level indicating the ground level, relative to the club head in its normal striking position, a pair of flanges formed integral with the sides of said top plate, adjacent one face of the club head, a pair of rear flanges formed integral with the end of said top plate, near the opposite club face, and means threadably attached to each of said rear flanges removably clamping the club head between said flanges.

4. A direction indicator for removable attachment to the head of a golf club, of the conventional type, for aligning said club head in the direction of movement of a ball, the club head remaining unaltered, comprising a top plate mounted above the club head, said top plate having an aperture formed therein, in substantial alignment with the ball-striking section of one face of the club, to enable a player to observe the ball through said aperture, a pointer formed integral with one end of said top plate in axial alignment with said aperture, the top plate having a pair of substantially parallel support members integral therewith, a spirit level

mounted between the support members, a housing supporting said spirit level, each end of said housing having a pair of ears integral therewith, each pair of ears being adjustably attached to the corresponding support member, one end of the sides of said top plate being folded, the free end of each of said folded sides being bent to form a flange, adjacent one face of the club head, a formed plate spring attached to each of said flanges, each of said springs having a clamping face engaging the adjacent face of the club head, a pair of rear flanges formed integral with the end of said top plate, near the opposite club face, a screw threadably attached to each of said rear flanges, and a swivel head attached to each of said screws, said flanges straddling the club head, the club head being clamped between the swivel head and the spring attached to the opposite flange.

5. A direction indicator for removable attachment to the head of a golf club, of the conventional type, for aligning said club head in the direction of movement of a ball, the club head remaining unaltered, comprising a top plate mounted above the club head, said plate having an aperture formed therein, in substantial alignment with the ball-striking position of one face of the club, to enable a player to observe the ball through said aperture, a pointer formed integral with one end of said top plate in axial alignment with the aperture, the section of the top plate, adjacent the aperture, having a plurality of graduations formed therein, the center of said graduations being in alignment with the center of the pointer, to indicate the position of the striking center of the club face relative to the ball, said top plate having a pair of substantially parallel support members formed integral therewith, a spirit level mounted between said support members, a housing supporting said level tube, each end of said housing having a pair of ears formed integral therewith, each pair of ears being clamped around the corresponding support member, to adjustably support the spirit level, said spirit level indicating the ground level, relative to the club head in its normal striking position, a pair of flanges formed integral with the sides of said top plate, adjacent one face of the club head, a formed plate spring attached to each of said flanges, each of said springs having a clamping face engaging the face of the club head, a pair of rear flanges formed integral with the end of said top plate, behind the opposite club face, and means threadably attached to each of said rear flanges removably clamping the club head between the threaded means and the springs.

6. A direction indicator for removable attachment to the head of a golf club, of the conventional type, for aligning said club head in the direction of movement of a ball, the club head remaining unaltered, comprising a top plate mounted above the club head, said top plate having an aperture formed therein, in substantial alignment with the ball-striking position of one face of the club, to enable a player to observe the ball through the aperture, a pointer formed integral with one end of said top plate in axial alignment with the aperture, the section of the top plate, adjacent the aperture, having a plurality of graduations formed therein, the center of said graduations being in alignment with the center of the pointer, to indicate the position of the striking center of the club face relative to the ball, said top plate having a pair of substantially parallel support members formed integral therewith, a spirit level mounted between said support members, a housing supporting said spirit level, each end of said housing having a pair of ears formed integral therewith, each pair of ears being clamped around the corresponding support member, to adjustably support the spirit level, said spirit level indicating the ground level relative to the club head, in its normal striking position, a pair of flanges formed integral with the sides of said top plate, adjacent one face of the club head, a plate spring attached to each of said flanges, each of said springs having a clamping face engaging the face of the club head, a pair of rear flanges formed integral with the end of said top plate, near the opposite club face, a screw threadably attached to each of said rear flanges, and a swivel head attached to each of said screws, said flanges straddling the club head, the club head being clamped between the swivel head and the spring attached to the opposite flange.
